Patented Mar. 15, 1966

204,066

THROWN BALL TARGET

Edwin J. Leahy, 1614 Greenwood Drive,
San Carlos, Calif.

Filed May 3, 1965, Ser. No. 85,084

Term of patent 14 years

(Cl. D34—5)

FIGURE 1 is a front elevational view of a thrown ball target showing my new design;

FIGURE 2 is a side elevational view thereof; and

FIGURE 3 is a fragmentary rear elevational view thereof.

I claim:

The ornamental design for thrown ball target, as shown.
